UNITED STATES PATENT OFFICE.

FRANK E. BOCORSELSKI, OF RICHMOND, VIRGINIA.

ROTARY DRILL.

1,131,991.

Specification of Letters Patent. Patented Mar. 16, 1915.

Application filed May 16, 1914. Serial No. 839,062.

To all whom it may concern:

Be it known that I, FRANK E. BOCORSELSKI, a citizen of the United States, and residing at Richmond, in the county of Henrico and State of Virginia, have invented 5 certain new and useful Improvements in Rotary Drills, of which the following is a specification.

This invention relates to rotary drills, 10 and particularly to the type known as "twist drills," and its primary object is to provide a drill which may be reversed end for end to drill from either end.

It is well known in the art that drill bits 15 provided with shanks frequently break at the point of juncture between the body of the drill and the shank, thus necessitating discarding of the drill and causing an appreciable waste.

20 The present invention aims to avoid this loss and expense by providing a reversible drill-bit which is entirely without end projections or shanks, and to effect the rotation of the drill by clamping means applied 25 to the body of the drill at diametrically-opposite points thereon.

By thus providing a reversible drill, my 30 invention makes it possible to reclaim broken discarded drills which have been rendered useless through the loss of their shanks.

The invention therefore consists broadly of a shankless reversible twist drill-bit.

The invention also includes features of 35 construction which will be fully described hereinafter in connection with the accompanying drawing which forms a part of this specification and the features of novelty of which will be set forth and defined in the 40 appended claim.

In the drawing: Figure 1 is a side elevation of a reversible drill embodying the invention. Fig. 2 is a transverse section on line 2—2 of Fig. 1.

45 The reference numeral 10 designates a twist drill provided at each end with a cutting point designated by the numerals 11 and 12.

The numeral 13 designates a spiral groove 50 extending from the upper end of the drill to a point mid-way of the length of the drill indicated by the line X—X to provide a spiral cutting edge 14 which terminates at

line X—X. From the line X—X at the center of the length of the drill, the groove 55 13 extends to the lower point 12 of the drill, which provides a spiral cutting edge 15 extending from the center of the drill to the lower point 12. In other words, the drill is shown with the cutting edge 14 extending 60 from the upper pointed end 11 to the line X—X, and the cutting edge 15 from the line X—X to the lower pointed end 12. As thus constructed, the drill is adapted to be reversed to operate with a right hand revolution from either end, and the diametrically opposite flat portions 16 of the body of the drill within the groove 13 are adapted to be engaged by suitable clamping arms or jaws of a rotating means. Various rotating devices may be employed for rotating the 65 drill in the manner indicated, but I have found that a chuck or drill holder provided with oppositely-disposed clamping arms having fingers to engage the drill at the 70 point 16, is well adapted for the purpose in view, and a drill holder or chuck especially designed for use with my improved reversible drill constitutes the subject matter 75 of a separate application for patent filed 80 by me May 16, 1914, Serial No. 839,061.

By reference to Fig. 2, it will be seen that the cutting edge 14 is suitably beveled and sharpened to effect the required spiral shearing action, the cutting edge being similarly 85 constructed.

It will be noted that the construction as illustrated in the drawings constitutes substantially two independent drills connected at the point X—X integrally to adapt the 90 drill to be readily reversed to make either of its ends available for drilling purposes.

It will be apparent that the invention entirely avoids the possibility of breakage at the point of juncture between the drill and 95 the usual ordinary shank, since I entirely dispense with the shank as a securing means for the drill. It will be also noted that by my invention, broken discarded drills may be reclaimed by forming a cutting point 100 thereon and adapting them to be engaged at a point intermediate their ends by a suitable clamping device connected with means for rotating the drill.

What I claim as new is: 105
A spirally grooved reversible drill-bit

having a spiral cutting edge extending for approximately half the length of the bit, and another cutting edge reversely disposed with relation to the first-named spiral cutting edge extending throughout the remainder of the length of the bit, thus adapting the bit for right-hand drilling at either end.

In testimony whereof I affix my signature in presence of two witnesses.

FRANK E. BOCORSELSKI.
